[57] CLAIM

The ornamental design for a bicycle frame, as shown and described.

DESCRIPTION

FIG. 1 is a perspective view of a bicycle frame showing our new design, the bicycle parts shown in broken lines are for illustrative purposes only and form no part of the claimed design;

FIG. 2 is a right side elevational view of the bicycle frame of FIG. 1, with the left side elevational view being a mirror image thereof;

FIG. 3 is a front elevational view of the bicycle frame of FIG. 1;

FIG. 4 is a rear elevational view of the bicycle frame of FIG. 1;

FIG. 5 is a top view of the bicycle frame of FIG. 1; and,

FIG. 6 is a bottom view of the bicycle frame of FIG. 1.
